UNITED STATES PATENT OFFICE.

ARCADY DEVIATKOFF, OF SAN FRANCISCO, CALIFORNIA.

TELEPHONE RELAY.

Application filed January 13, 1926. Serial No. 80,857.

This invention relates to telephone relays used in transmitting over the telephone or radio telephone, the invention having more particular reference to a novel type of telephone relay. The invention has for an object the provision of an improved telephone relay which may be more easily adjusted.

For further comprehension of the invention, and of the objects and advantages thereof, reference will be had to the following description and accompanying drawings, and to the appended claims in which the various novel features of the invention are more particularly set forth.

Fig. 1 of the drawing is a side elevational view of my improved device.

Fig. 2 is a bottom view of my improved telephone relay, certain parts being removed to show more clearly the working parts thereof.

Fig. 3 is a sectional view taken on the line 3—3 of Figure 2.

Fig. 4 is a sectional view taken on the line 25 4—4 of Figure 3.

Fig. 5 is a sectional view taken on the line 5—5 of Figure 3.

Fig. 6 is a schematic diagram of the wiring.

As here embodied my improved telephone relay comprises a suitable base 10 having attached at its lower edge by screws 50 a supplementary base 11 and at the lower edge thereof a suitable standard 12, preferably of rubber. The base 10 has a recess 13 at its upper side, supporting a bracket 14 provided with a threaded portion 14' to accommodate a suitable removable casing 15, having a suitable cover 48 provided with a disc 49 preferably of glass to present a neat appearance.

The upper portion of bracket 14 is provided with female threads 14^a having screwed therein pole pieces 37 of an electro-magnet. The pole pieces are semi-circular below points 37^a as clearly shown in Figure 4, while above these points there are arcuate segments as clearly shown in Figure 5. Along the adjacent ends these pieces 37 are separated by insulation 51. The insulation washer 52 separates three different windings. The lower winding 38^a completely encircles the pole pieces 37, and the ends of said winding connect respectively to posts 34' and 36'

and therefrom to terminals 34 and 36. The central winding 38^b likewise completely encircles the pole pieces 37, and the ends of said winding are connected respectively to posts 34' and 32' and therefrom to terminals 34 and 32. The upper winding 38 is composed of two windings connected in series, and wound in opposite directions around the arcuate portions of the pole pieces 37, as shown in Figure 5, and the ends of the winding are connected respectively to posts 31' 65 and 33' and thereafter to terminals 31 and 33.

The base 10 has a washer 53 fastened thereto by screws 54, and is provided with female threads to accommodate support 20 70 having a chamber at its upper end, the bottom of said chamber housing a disc 23, while the chamber is filled with carbon, or coal granulus, and the upper end of the chamber is closed by a mica diaphragm 18 supported 75 at its outer edges by the ring 19, said diaphragm having centrally attached a rod 17 connected with a metallic disc 55 beneath said mica diaphragm and bearing against said granulus, while the upper end of the said rod 17 is provided with an anchor 16 extending over the ends of pole pieces 37, and having electrically attached a very fine flexible wire 56 the other end of which is attached to post 32' and thereafter to 85 terminal 32.

The disc 23 in the bottom of the granulus chamber is connected to a threaded rod 22 supported by a rotatable member 25, which may be rotated by means of knob 26 allowing a very minute adjustment by pinions 27 and 28, rotatably mounted and meshing with the gears 29 and 30, the gear 30 being attached to the said member 25, and said pinions and gears are supported by plate 39. 95

A supporting body 57 supports a bearing for member 25, and also a spring 24 operatively connected to normally press disc 23 against the granulus. The wire 58 forms an electrical connection from 57 to said disc 23, and said wire 58 connects to terminal 35. 100

Leads carrying the incoming signals to be relayed are connected respectively to terminals 31 and 33, having connections as before mentioned to windings 38. Across terminals 34 and 36, a battery 60, and adjustable resistance 61 are connected, said ter-

2

minals as before explained having connections to winding 38^a thereby energizing poles of thus formed electromagnet, but of course the invention could also be operated 5 with the use of a permanent magnet instead. Terminals 32 and 35 are connected to a circuit including a battery 62, and since, as before explained 32 connects to 16 thereafter to the upper side of the granulus, while the 10 lower side of the granulus is connected to 35, thus forming a microphonic arrangement 63, this circuit will be the amplified circuit and have the incoming signals impressed therein, which may be received in telephone 15 receivers 64 or may be again relayed. The winding 38^b connects between terminal 34 and 32, or in other words forms an inductance to the pole pieces 37 connected between the microphonic circuit and the elec- 20 tromagnet energizing circuit. The last mentioned circuit 38^b adds to the quality of the invention, but the invention operates even if this circuit and winding is eliminated.

25 By manually adjusting 26, thereby adjusting the pressure in the granulus chamber, the device can be very accurately set. The incoming signals from terminals 31 and 33 vibrate the anchor 16 connected by rod 30 17 to the granulus chamber, thereby changing the pressure between the coal granulus, and effecting a resultant changing in the electrical resistance of said granulus, im- 35 pregnating similar signals as the incoming ones into the microphonic circuit, which of course, is a circuit carrying a current of greater strength than the incoming circuit current.

While I have above described the pre- 40 ferred form, construction and arrangement of the several elements employed, it will be understood that the device is, nevertheless, susceptible of considerable modification therein, and that parts illustrated and de- 45 scribed as separate details may be combined, and I therefore reserve the privilege of resorting to all such changes as may be fairly embodied within the spirit and scope of the invention as claimed.

50 Having thus described my invention what I claim as new, and desire to secure by

Letters Patent of the United States is as follows:—

1. In a device of the class described, having a microphone, and an operating knob with a train of gears for adjusting the pressure of the microphonic substance of said microphone, the combination of a base, a supplementary base attached to the bottom of said base, said train of gears being mounted in said bases, a washer fastened to the upper side of said base, a support threadedly engaged in said washer, said support having a chamber at its upper end to house said microphone, a member engaging against said microphone, a threaded rod connected to said member, a rotatable member threadedly engaging said rod, said rotatable member being connected to the last gear of said train of gears, a body supported in said base, said body forming a bearing for said rotatable member, and an expansion spring acting between said body and said member which engages against said microphone.

2. In a device of the class described, having a microphone, and an operating knob with a train of gears for adjusting the pressure of the microphonic substance of said microphone, the combination of a base, a supplementary base attached to the bottom of said base, said train of gears being mounted in said bases, a washer fastened to the upper side of said base, a support threadedly engaged in said washer, said support having a chamber at its upper end to house said microphone, a member engaging against said microphone, a threaded rod connected to said member, a rotatable member threadedly engaging said rod, said rotatable member being connected to the last gear of said train of gears, a body supported in said base, said body forming a bearing for said rotatable member, a flange depending from said body, and an expansion spring acting between said flange and said member which engages against said microphone.

In testimony whereof I have affixed my signature.

ARCADY DEVIATKOFF.
